UNITED STATES PATENT OFFICE.

RALPH A. BELMONT, OF NEW YORK, N. Y., ASSIGNOR TO BEAVER MACHINE AND TOOL CO., INC., OF NEWARK, NEW JERSEY, A CORPORATION OF NEW JERSEY.

FEED-THROUGH SWITCH.

1,355,121.

Specification of Letters Patent.

Patented Oct. 12, 1920.

Application filed March 13, 1918. Serial No. 222,072.

To all whom it may concern:

Be it known that I, RALPH A. BELMONT, of New York, in the county and State of New York, have invented a new and useful 5 Feed-Through Switch, of which the following is a specification.

A feature of my invention is that the switch is mounted on a support which is separate from the casing, one of the advantages of this construction being that if the 10 switch burns out the casing is still available for use and another of the advantages being that the wiring is very easily done, the wires being connected to the support and then the 15 casing applied.

Another feature of my invention is a casing which is split, preferably longitudinally, and which surrounds the switch and is held thereto.

20 Another feature consists in fastening means at both ends of the casing and preferably I use means which can be snapped in place, such as split rings.

Another feature consists in providing a 25 neck or necks to surround the conductors, the neck or necks preferably coöoperating with the fastening means.

Other features will be pointed out below.

In the drawing—

30 Figure 1 is a plan of my switch with the casing applied;

Fig. 2 is a plan with one casing member removed;

Fig. 3 is a reverse plan with the other casing member removed;

Fig. 4 is a plan of the support;

Fig. 5 is a central vertical section;

Fig. 6 is a vertical section on line 6—6 of Fig. 3;

40 Fig. 7 is a plan of the movable contact;

Fig. 8 is an elevation of the movable contact; and

Fig. 9 is an elevation of the switch with the casing applied.

45 The support A for the fixed and movable contacts is a substantially cylindrical block of porcelain or other insulating material cut away at a and a' so as not to interfere with the push buttons and also having depressions

50 a^2 and a^3 adjacent to the fixed contact screw heads hereinafter described so as to permit the ends of the movable contact to sink slightly as they approach the fixed contacts and thus make a very efficient contact. Support A has a recess to receive a metal plate

B which has a wall at one end having an upper portion b and a lower portion b' , these portions being spaced to receive the actuating bar hereinafter described. At the other end of the plate is a similar wall having upper portion b^2 and lower portion b^3 . The metal plate has a slot b^4 and holes b^5 , b^6 and b^7 to coöperate with other parts described below, holes b^5 and b^7 being threaded. On the reverse face of support A are depressions d 60 and d' to receive the heads of screws D and D', which screws pass through the support, the former engaging threaded hole b^5 and the latter engaging threaded hole b^7 to hold the metal plate B in place. The reverse face 70 of the support is depressed at d^2 to permit ready manipulation of wire E in attaching the latter to the binding post E' which is carried by plate E², the latter being held in place by means of threaded connection with the shank f of a screw which passes through the support or base A, the head F of the screw acting as a fixed contact. Similarly the reverse face is depressed at d^3 for manipulation of wire G in attaching the latter 75 to binding post G' which is carried by plate G², the latter being held in place by means of threaded connection with the shank g of another screw which passes through the support, the head g' acting as the other fixed 80 contact.

The movable contact member H has a stud riveted to it the shank h of which enters hole b^6 and acts as a pivot for the member H. Near the contact ends the member H is crimped at h' and h^2 to give the ends great resiliency so that they will efficiently engage the fixed contacts. 90

The push buttons K and K' are cut away as shown so as not to strike the support and 95 they are mounted on the ends of bar K² which is guided between the upper portions b and b^2 and the lower portions b' and b^3 , said bar being provided with depending lugs k and k' which engage the walls of the 100 metal plate B to limit the movement of the bar K².

A coiled bow spring M has one end m passing through the movable contact member and hooked or bent thereunder the 105 hooked portion riding in slot b^4 . The other end m' of the spring is curved around and hooked into the bar K² and when the bar K² is pushed upward in Fig. 3 end m' of the spring is carried upward and when said end 110

passes the line extending from the end m through the pivot of the movable contact the movable contact will be actuated out of engagement with the fixed contacts and the reverse movement of the bar K^2 will give reverse movement to the movable contact.

It will be clear that the fixed and movable contacts are mounted on the support or base and the wires E and G connected thereto, the wire N resting along the edge of the support, the structure thus forming a complete entity apart from the casing which is split longitudinally to form two members P and P' , the flat face p of member P engaging the flat face p' of member P' . Member P has a neck portion p^2 at one end and p^3 at the other end, member P' having similar neck portions p^4 and p^5 , the portions p^2 and p^5 coöperating to surround the conductors at one end of the device while the portions p^3 and p^4 coöperate to surround the conductors at the other end of the device. Member P is grooved at p^6 and p^7 to receive the split rings described below and has a deep recess p^8 to receive the spring M and has also a raised circular rib p^9 to enter member P' so as to prevent relative movement of face p along face p' other than rotary movement. Member P' is grooved at p^{10} and p^{11} to receive said split rings and has recess p^{12} to hold the support against sideways or lengthwise movement and additional recesses p^{13} and p^{14} to receive the binding posts, space p^{15} in Fig. 3 receiving the rib p^9 .

When the switch parts and the wires have been attached to the support as a separate entity the two parts of the casing are applied and the split rings R and R' are snapped into the grooves of members P and P' to hold said members together, the portions p^{16} and p^{17} of rib p^9 by engagement with wires E and G tending to prevent removal of the support from recess p^{12} .

45 What I claim is:

1. A device of the character described comprising a base of insulating material; switch mechanism, all of whose parts in-

cluding terminals are mounted on said base; a longitudinally split casing for said elements comprising a plurality of parts of insulating material, said switch mechanism itself being entirely disconnected from said casing; means to hold said parts of the casing together; an electrical conductor connected to one of said terminals; another electrical conductor connected to the other of said terminals; and a third electrical conductor passing through said casing.

2. A device of the character described comprising a base of insulating material; switch mechanism, all of whose parts including terminals are mounted on said base; a longitudinally split casing for said base and switch mechanism and comprising a plurality of parts of insulating material, neither said base nor any part of said switch mechanism having any fixed connection with said casing but being held in place by said casing; means to hold said parts of the casing together; an electrical conductor connected to one of said terminals; another electrical conductor connected to the other of said terminals; and a third electrical conductor passing entirely through said casing but having no fixed connection therewith.

3. A device of the character described comprising a base of insulating material; a switch mechanism, all of whose parts including terminals are mounted on said base; a longitudinally split casing for said base and switch mechanism and comprising a plurality of parts of insulating material, neither said base nor any part of said switch mechanism having any fixed connection with said casing, but being held in place by said casing; means to hold said parts of the casing together; an electrical conductor connected to one of said terminals; another electrical conductor connected to the other of said terminals; and a third electrical conductor which is flexible and covered with insulating material and which passes entirely through said casing but has no fixed connection therewith.

RALPH A. BELMONT.
